Attorney, Agent, or Firm—Ostrolenk, Faber, Gerb & Soffen, LLP**[57] CLAIM**

The ornamental design for a programmable pump for infusion, as shown and described.

DESCRIPTION

FIG. 1 is an exploded front elevation view of a first embodiment of the programmable pump for infusion of the present invention;

FIG. 2 is an exploded top view thereof;

FIG. 3 is an exploded bottom view thereof;

FIG. 4 is an assembled front elevation view of the first embodiment of the programmable pump for infusion;

FIG. 5 is a rear elevation view thereof;

FIG. 6 is a top elevation view thereof;

FIG. 7 is a bottom elevation view thereof;

FIG. 8 is a side elevation view thereof;

FIG. 9 is a front elevation view of a second embodiment of the programmable pump for infusion of the present invention;

FIG. 10 is a perspective view of the cassette shown in FIGS. 1-9.

FIG. 11 is a front elevational view of the programmable pump for infusion, showing my new design used in connection with a pair of cassettes;

FIG. 10 is a rear elevation view thereof;

FIG. 11 is a side elevation view thereof;

FIG. 12 is a top elevation view thereof; and,

FIG. 13 is a bottom elevation view thereof and.
